Primary Examiner — Ramzi Almatrahi(74) *Attorney, Agent, or Firm* — Venable LLP(57) **CLAIM**

The ornamental design for a digital camera, as shown and described.

DESCRIPTION

FIG. 1 is a front view of a digital camera showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The broken lines depict portions of the digital camera in which the design is embodied that form no part of the claimed design. Additionally, the dash-dot broken lines denote the boundary of the claim and form no part of the claimed design.
